UNITED STATES PATENT OFFICE

2,238,760

LAPPING APPARATUS

David A. Wallace, Detroit, Mich., assignor to
Chrysler Corporation, Highland Park, Mich., a
corporation of Delaware

Original application July 22, 1936, Serial No.
91,851. Divided and this application August 1,
1938, Serial No. 222,510

6 Claims. (CL 51—67)

This invention relates to improved apparatus for lapping surfaces and is a division of my application, Serial No. 91,851, filed July 22, 1936 which has matured as Patent No. 2,195,047, dated March 26, 1940.

More particularly, the invention pertains to lapping of surfaces of apparatus and parts thereof which operate in rubbing, sliding or rotative bearing-like or frictional contact with other parts.

Heretofore, in polishing, lapping or otherwise finishing surfaces, it has been the practice to produce relative movement, mainly in one direction only, between the surfaces of the work and the lapping means. In some instances combinations of different directional movements have been employed in an effort to avoid scoring of the surface operated upon by repeated action of isolated hard particles of the lapping element on substantially the same areas of the work. The relative movement in one direction has, however, been of a relatively low order of velocity as compared to the relative movement in another direction, and consequently, the scratch lines, scores or inscriptions traced on the work by isolated hard particles in the lapping surface have not been so disturbed and cross-hatched as to provide finished surfaces of actual mirror-like smoothness directly by lapping operations.

Polishing with extremely fine abrasives, such as rouge, has been required after the lapping operation, to produce the desired degree of smoothness and finish. In this connection it should be noted that while polishing of this character improves the appearance of the surfaces it does not materially change its physical smoothness. That this is true can readily be seen by microscopic observation of conventionally lapped and polished surfaces by which it is found that the multiplicity of minute ridges between adjacent scratch lines or scores are not actually removed. The polishing compound merely forms a luster on the sides of such ridges which give the final surface an appearance of much greater smoothness than actually exists.

I have found that by producing relative movements of respectively different ranges of speed and in different directions, preferably at right angles, between the surface operated upon and the lapping surface, actual smoothness is directly obtained by lapping and such smoothness is of a much different and superior kind than that resulting from conventional lapping followed by polishing operations.

One of the main objects of the invention is to

provide improved lapping apparatus by which physically smooth and mirror-like surfaces can be directly formed by lapping operations without producing a deceitful luster such as that formed by polishing the side surfaces of ridges of presumably, but not actually, smooth surfaces.

Another object of the invention is to provide apparatus of this character by which the inscriptions traced on the surface operated upon by localized hard particles in the lapping surface can be brought to a desired angular cross-hatched relationship such that the resulting scratch lines are accordingly so repeatedly cross-hatched as to destroy their normal roughness producing effect.

15 A further object of the invention is to provide apparatus of this character by which the reciprocating movement of the lapping element is maintained at a sufficiently high velocity and frequency to produce smooth surfaces free from grooves and scores with a limited amount of reciprocatory movement.

20 An additional object of the invention is to provide apparatus of this character by which a lapping element can be conveniently reciprocated, during application thereof to a rotating piece of work, at a relatively high rate of speed of a vibratory order.

25 A still further object of the invention is to provide an improved lapping device which will operate a plurality of conveniently attachable and detachable lapping elements so as to facilitate adaptation of the device to the lapping of a plurality of different types of pieces of work.

30 Another object of the invention is to provide lapping apparatus of this character by which the relative movement between the lapping element and the work in one direction is of a reciprocatory nature and which movement varies in velocity from zero at opposite ends of the stroke while maintaining a substantially high velocity throughout the main portion of the stroke.

35 Other objects of the invention are to provide an improved lapping device by which either the inner or outer surfaces of a pair of annular members, such as bearing rings, can be simultaneously lapped by a single reciprocating member and in accordance with the invention; and to provide lapping apparatus of this character which is adapted to simultaneously lap frusto-conical surfaces of a pair of bearing members.

40 An illustrative embodiment of the invention is shown in the accompanying drawing, in which:

45 Fig. 1 is a fragmentary plan view, partly in section, of an apparatus embodying the invention for lapping a pair of bearing elements.

Fig. 2 is a fragmentary, side elevational view, partly in section, of the apparatus shown in Fig. 1.

Fig. 3 is a fragmentary vertical sectional view taken on the line 3—3 of Fig. 2.

The form of the invention shown in the drawing illustrates an application of my improved lapping apparatus and process whereby the internal surface of two bearing members may be simultaneously lapped in accordance with the invention, whether such surfaces are cylindrical or frusto-conical in shape. The apparatus includes a substantially horizontal base structure 133 on which is slidably mounted a fixture 134 comprising a casing 135 in which a tubular shaft 136 is journaled. The tubular shaft 136 is provided with a pulley 137 which is drivingly connected by a belt 138 with a shaft 139 of a motor 140, or other suitable driving means, preferably mounted on top of the casing 135. As illustrated in Fig. 1, two fixtures 134 are slidably mounted on the base 133 and each is provided with a casing 135 having a tubular shaft drivingly connected with the motor 140. Inasmuch as these units are identical, the description of one would serve for the description of the other.

Mounted on the adjacent ends of the tubular shafts 135 of each unit is a work holder comprising a cylindrical cup 141 having a recess 142 for receiving a bearing member 143 and a counter-bored recess 144 in which a work displacing member 145 is slidably mounted. The work displacing member 145 has a stem 146 extending axially through the tubular shaft 136 beyond the pulley 137. The external end of the stem 146 is provided with an enlarged head 147 for facilitating driving of the work 143 from the recess 142 of the work holding member. Each unit is so disposed as to bring the axis of rotation of the work holders into such angular relationship as will align the surfaces 148 of the work 143 in the manner illustrated in Fig. 1. These surfaces are frusto-conical and the units are arranged in the angular relationship shown in this figure.

Disposed between the work holders 141 of the units is a lapping fixture, generally designated by the numeral 149, which, in this form, is disposed horizontally. The lapping fixture includes a support 150 on which the body portion of the fixture 151 is adjustably mounted. The body portion 151 may be adjustably fixed in a selected position by clamping bolts 152 which extend through elongated apertures in the body portion 151 and which are threaded in apertures formed in the support 150. Formed in one end of the body portion 151 is a recess 153 in which a block 154 is slidably mounted. Pivotally attached to the block 154 by a removable pin 155 is a lapping element holder 156 having a pair of lapping elements 157 thereon, each of which is engaged with the surface 148 of one of the bearing members 143. The lapping element 157 preferably comprises an abrading stone structure, or any suitable abrading material. The block 154 is provided with a slot 158 in which an eccentric pin 159 is carried by a shaft 160 of a motor 161. The motor 161 is mounted on the body portion of the lapping fixture or otherwise suitably supported. In order to yieldably urge the lapping elements 157 against the surface of the work operated upon, the longitudinal bar of the holder 156 may comprise a strip of resilient metal which may be deflected slightly by proper adjustment of the body portion of the lapping fixture so as

to firmly hold the lapping elements in contact with the work.

Rapid removal of work from and mounting of work in the work holders may be facilitated by the employment of a pneumatic cylinder 162 for sliding each unit relative to the base structure 133, in order to move the work away from the lapping fixture 149. In this form of the invention, the velocity of the reciprocatory movement of the lapping elements produced by the operative driving connection thereof with the motor 161 will likewise be predetermined with respect to the rotative movement of the work in order to produce the foregoing results.

The surfaces lapped by apparatus embodying the invention and in accordance with my improved lapping process may be brought to a mirror-like actual physical smoothness much superior to that produced by the combination of a conventional lapping process followed by polishing. Of course, if it is desired to further finish surfaces which have been lapped in accordance with the invention, such surfaces may be subjected to polishing treatment with rouge or other suitable fine abrasive. Surfaces lapped in accordance with the invention are found to be free from excessive scratches, scores and grooves, such as have resulted in prior lapping operation from repeated action of localized hard areas of the lapping element upon substantially the same areas of the work or areas adjacent thereto. The inscriptions traced upon the work by such localized hard areas of the lapping element are so distributed and cross-hatched as to eliminate their roughness producing effect.

During operation of the foregoing apparatus, the work is rotated continuously in one direction and the lapping elements are reciprocated in a direction substantially parallel to the axis of rotation of the work. The linear velocity of these respective different directional movements are so predetermined as to bring the resultants of the movements during successive half cycles of the reciprocatory movement into predetermined angular relationship with respect to each other. It is preferable to cause the resultants of the movements produced during successive half cycles of the reciprocatory movement to intersect at substantially right angles to each other. To accomplish this, the linear velocity of the surface operated upon and the linear velocity of the lapping elements must be substantially equal. However, since the velocity of the reciprocatory movement varies, this condition is not maintained at all times but is approached throughout the main portions of the strokes of the lapping elements. Localized hard areas of the lapping surface, therefore, trace inscriptions on the surface of the work during successive half cycles of the reciprocatory movement which are cross-hatched at a plurality of different angles forming an heterogeneous arrangement of cross-hatched scratch lines, none of which develop into deep grooves or scores. While it is preferable to so predetermine the linear velocity of the movement of the work and movement of the lapping elements as to bring the main portions of the scratch lines to approach right angle relationship with respect to each other, it is found that excellent results are obtained when the angularity of the lines traced during successive half cycles of the reciprocatory movement is such that the minimum angle therebetween is substantially forty degrees. In other words, the resultant of the two directional move-

ments may vary from an inclination of substantially twenty to substantially seventy degrees to the path of reciprocatory movement. For the purpose of illustration, a cylindrical surface of substantially three and one-eighth inches in diameter would be rotated at approximately sixty R. P. M. and the lapping elements would be reciprocated at a rate of substantially 900 cycles per minute.

In the lapping of surfaces in accordance with the invention during which the lapping element is reciprocated at a relatively high speed, it is found that the abrasive action of the lapping elements is rapid while the ridges formed during turning or other machining of the surfaces are being removed. As soon as the ridges are removed to their base line, the abrasive action decreases materially and further removal of metal is substantially discontinued. By virtue of this characteristic of the improved lapping process, surfaces can be brought to a high degree of smoothness in a relatively short time and without danger of removing sufficient material to render the articles undersize. The smoothness resulting from the actual removal of the ridges without introducing other ridges by application of the lapping elements to the surface is of a much superior order than the mere lustrous finish resulting from polishing the side surfaces of the ridges. The large number of strokes of the lapping elements across the ridges in a direction substantially normal to their lengths, resulting from reciprocation of the lapping elements at a rate of a vibratory order, assures removal of the ridges and not mere polishing or partial flattening thereof.

Although but one specific embodiment of the invention has been herein shown and described, it is understood that various changes of details of construction and operation may be made without departing from the spirit and scope of the invention.

What I claim is:

1. Apparatus for simultaneously lapping surfaces of a pair of pieces of work including a pair of work supporting and rotating members arranged with their work supporting ends disposed inwardly in spaced relationship with respect to each other, a lapping fixture located between said work supporting ends of said members including a reciprocable lapping element adapted to simultaneously engage surfaces of pieces of work mounted on each of said members respectively, and driving means on said fixture for reciprocating said lapping element.

2. Apparatus for simultaneously lapping surfaces of a pair of pieces of work including a pair of work supporting and rotating members arranged with their work supporting ends disposed inwardly in spaced relationship with respect to each other, a lapping fixture located between said work supporting ends of said members including a reciprocable support, a lapping element pivotally mounted on said support and reciprocable in unison therewith and adapted to simultaneously engage surfaces of pieces of work mounted on each of said members respectively, and driving means on said fixture for reciprocating said lapping element.

3. Apparatus for simultaneously lapping frusto-conical surfaces of a pair of bearings including a pair of work supporting and rotating members having axes arranged in opposed angularly extending relationship with respect to each other and having work supporting ends directed toward but spaced from each other, a lapping fixture located between said work supporting ends of said members including a reciprocable lapping element adapted to simultaneously engage the frusto-conical surface of each bearing respectively, and driving means on said fixture for reciprocating said lapping element.

4. Apparatus for simultaneously lapping surfaces of a pair of pieces of work including a pair of work supporting and rotating members arranged with their work supporting ends disposed inwardly in spaced relationship with respect to each other, a lapping fixture located between said work supporting ends of said members including a reciprocable lapping element adapted to simultaneously engage surfaces of pieces of work mounted on each of said members respectively, and means for yieldably urging said elements against said surfaces and mechanism for simultaneously drivingly rotating said work and reciprocating said lapping element at a speed of a vibratory order.

5. Apparatus for simultaneously finishing surfaces of a pair of pieces of work including a pair of work supporting members arranged with their work supporting ends disposed inwardly in spaced relationship with respect to each other, a fixture located between said work supporting ends of said members including a reciprocable support, an abrading element carrier including a resilient element carried by said reciprocable support and located between the latter and portions of said work, abrading elements on said carrier engageable with said pieces of work and adapted to be yieldably urged thereagainst by said resilient element, and mechanism for drivingly reciprocating said reciprocable support, carrier and abrading elements in unison.

6. Apparatus for finishing a frusto-conical surface of a piece of work including a slidably adjustable tool support, a tool reciprocably mounted on said support for linear movement in a predetermined course transversely of the direction of adjustable movement of said support, said tool comprising a resilient arm having a free end portion, an abrading element on said free end portion yieldably urged by said arm against said work, mechanism for drivingly reciprocating said tool, means for positioning and rotatably supporting said work for rotation about an axis coincident with the central axis of said surface and so inclined with respect to the linear course of reciprocation of said tool as to bring a portion of said surface into parallel relationship with respect to said course of reciprocation of said tool, means for releasably holding said tool support in a selected position to maintain said abrading element in contact with said surface, and apparatus for drivingly rotating said work.

DAVID A. WALLACE.
